ELECTRONIC THERMOMETER

George E. Chilton, 144 Valley Road,
Haworth, N.J. 07641

Filed Aug. 30, 1968, Ser. No. 13,339

Term of patent 14 years

Int. Cl. D10—07

U.S. Cl. D52—7

FIG. 3

FIG. 2

FIG. 1

FIG. 5

FIG. 6

FIG. 4

FIG. 1 is a front view taken in elevation of an electronic thermometer showing my new design;

FIG. 2 is a bottom view thereof;

FIG. 3 is a top view thereof;

FIG. 4 is a rear view taken in elevation thereof;

FIG. 5 is a side view as seen from the left edge of FIG. 1; and

FIG. 6 is a side view as seen from the right edge of FIG. 1.

The dominant features of the design reside in the full line portions thereof.

I claim:

The ornamental design for an electronic thermometer, substantially as shown and described.
